TRIGGER SAFETY LOCK FOR FIREARMS

Edward E. Schaefer, River Forest, Ill. (% Central Specialties Co., 3813 N. Harlem Ave., Chicago 34, Ill.)

Filed July 6, 1962, Ser. No. 70,819

Term of patent 14 years

(Cl. D30—1)

FIG. 1 is a side elevational view of a trigger safety lock for firearms showing my new design;

FIG. 2 is a view similar to FIG. 1 showing the opposite side thereof;

FIG. 3 is an enlarged top plan view thereof;

FIG. 4 is an end elevational view of the left end thereof as viewed in FIG. 1; and

FIG. 5 is an end elevational view of the right end thereof as seen in FIG. 1.

The portion of a gun shown in broken lines in FIG. 1 is for illustrative purposes only.

I claim:

The ornamental design for a trigger safety lock for firearms substantially as shown and described.
